UNITED STATES PATENT OFFICE.

THEODORE CHANOCK, OF CHICAGO, ILLINOIS.

DESIGN FOR A STAND FOR A TABLE LAMP.

Application filed February 3, 1926. Serial No. 16,379. Term of patent 3½ years.

To all whom it may concern:

Be it known that I, THEODORE CHANOCK, a citizen of the United States, residing at Chicago, in the county of Cook and State of Illinois, have invented a new, original, and ornamental Design for a Stand for a Table Lamp, of which the following specification, reference being had to the accompanying drawings, forms a part thereof.

view of a stand for a lamp, the balance of the ornamentation within the dotted lines being a repetition of the fragment shown; and

I claim:

The ornamental design for a stand for a table lamp, substantially as shown.

THEODORE CHANOCK.
